UNITED STATES PATENT OFFICE.

CHARLES DONAT RICHARD, OF NEW BRIGHTON, NEW YORK, ASSIGNOR TO WESTERN ELECTRIC COMPANY, INCORPORATED, OF NEW YORK, N. Y., A CORPORATION OF NEW YORK.

ELECTRICALLY-OPERATED TIMING APPARATUS.

1,412,574.

Specification of Letters Patent. Patented Apr. 11, 1922.

Application filed September 3, 1920. Serial No. 407,958.

To all whom it may concern:

Be it known that I, CHARLES D. RICHARD, a citizen of France, residing at New Brighton, in the county of Richmond, State of 5 New York, have invented certain new and useful Improvements in Electrically-Operated Timing Apparatus, of which the following is a full, clear, concise, and exact description.

10 This invention relates generally to timing apparatus and particularly to apparatus for timing a series of electrical impulses.

It is the object of the invention to provide a device of this character which shall be 15 simple and accurate and automatically operative.

This is accomplished by the invention in its preferred form by providing a stepping magnet operated by the electrical impulses 20 to be measured which rotates a cam to release a time indicating device. At the end of the series of impulses the cam operates to stop the timing device, thereby recording the speed at which the impulses occurred.

25 The device in its preferred form is particularly useful to time the operation of automatic telephone calling dials. To give satisfactory results, such dials or impulse senders are generally adjusted so that the 30 impulses occur at the rate of ten per second. Any substantial deviation from this rate materially affects the efficiency of the impulse sender. When the impulse timing mechanism is used to time the operation of 35 a calling dial, ten impulses are dialed. The cam above referred to is constructed so that at the first impulse the timing mechanism is started and at the tenth impulse is stopped by the cam so that an accurate time record 40 is made.

The invention in its preferred form is shown in the drawings in which Fig. 1 shows a view of the impulse and time recording means; Fig. 2 shows a plan of the 45 clockwork timing mechanism, and the impulse operative mechanism cooperating therewith; Fig. 3 shows a view of the device along the line 3—3 (Fig. 2) showing the operation of the stepping magnet and the 50 associated cam; Fig. 4 shows a view taken along the line 4—4 (Fig. 2) and shows the means for regulating the timing apparatus and the cam and associated parts. In the 55 various figures like parts are designated by

The spiral spring 1 mounted within drum 2 is adapted to drive shaft 3. Pinned on the shaft 3 is a ratchet wheel 4 which engages with pawl 5 mounted on spur gear 6. Spur gear 6 is adapted to drive pinion 7 60 which is mounted on sleeve 8 to which are also integrally attached the escapement wheel 9 and the spur wheel 10. The sleeve 8 revolves freely on the shaft 14. Escapement wheel 9 is provided with an escape- 65 ment 11 of any suitable type such as is ordinarily used in clock movements. Spur wheel 10 drives the spur wheel 11 which rotates freely on the shaft 3. Spur wheel 11 is attached to spur wheel 12 by means of a bushing 13. Spur wheel 12 is in engagement with wheel 15 which revolves freely on shaft 14. To the shaft 14 is attached a ratchet wheel 16 which carries a drum 17. Mounted 70 on the spur wheel 15 are two spring members 18 which are adapted to grip the drum 17 on which they normally rub. The pointer 19 is pinned fast to the shaft 14 and revolves therewith. On two supporting members 20, 21 is pivoted a shaft 22 to which is 75 pinned a pawl 23 which engages with the teeth of the ratchet wheel 16.

Motion is normally prevented in the pointer 19 by the pawl 23 which engages the ratchet wheel 16, but when the pawl 23 is 80 withdrawn, friction between the springs 18 and the drum 17 produces rotation in the pointer 19.

The electromagnet 24 suitably mounted on the standard 25 is adapted to attract, when 85 energized, an armature 26 attached to the bell crank lever 27, pivotally supported on the support 28. Operating pawl 56 is adapted to rotate the ratchet wheel 57 upon motion of the armature 26 toward the magnet 24. A locking pawl 55 is provided to prevent the backward rotation of the ratchet wheel 57. For each time that the armature 26 is attracted to the magnet 24, the ratchet wheel 57 steps one tooth. Twenty teeth are 90 provided on the ratchet wheel 57, so that for ten impulses of the magnet 24, the ratchet wheel 57 is rotated one-half revolution. A coil spring 29 is provided on the bell crank lever 27 to keep the operating pawl 56 95 pressed against the teeth of ratchet wheel 57. The ratchet wheel 57 is mounted on a sleeve 30 which rotates freely on the shaft 14. The sleeve 30 carries a pointer 31 which is adapted to rotate concentrically with pointer 19, 110

Mounted on the sleeve 30 is a cam wheel 32 which is provided with two notches, 33 and 34. On the shaft 22 is pinned a lever 35 having a toothed end 36 which fits into the 5 notches 33 and 34.

Normally the mechanism is as shown in Fig. 3. As soon as the first impulse of the series to be timed energizes the magnet 24, the cam 32 rotates, throwing the point 36 10 of the lever 35 out of the notch 34, rotating the shaft 22 to disengage the pawl 23 from the toothed wheel 16 and allowing the pointer 19 to rotate. The timing mechanism is regulated so that pointer 19 rotates 15 at the rate of one revolution per two seconds. If the impulses energizing the magnet 24 are sent at the rate of 10 per second the pointer 31 will rotate also at the rate of one revolution per two seconds. At the 20 tenth impulse, the point 36 of the lever 35 drops into the notch 33 of the cam 32, since the notch 33 is diametrically opposite to the notch 34. The pawl 23 engages with the wheel 16 and stops the rotation of the 25 pointer 19. If the impulses are sent at the proper speed the pointers 19 and 31 will rotate together and stop together. If the impulses have been sent either fast or slow, the pointer 31 will accordingly be either 30 behind or before the pointer 19.

The mechanism as described is mounted on a suitable base 37 and provided with a suitable cover 38. On the face of the cover 38 is provided a dial graduated in tenths and 35 fiftieths of a second to accurately indicate the time of the impulse-sending. In order to return the pointers 19 and 31 to their normal positions after test has been made, a rotatable arm 39 is provided mounted on 40 support 40 on the face of the casing 38.

The spring 1 is wound by means of a suitable handle 41 on the shaft 3.

Binding posts 42 are provided on the base 37 for connection with conductors by means 45 of which the electrical impulses to be timed are impressed on the magnet 24. In order to regulate the mechanism a dial as shown in Fig. 4 of the pointer 43 is provided which rotates with the spur wheel 44 mounted on 50 the shaft 3. Spur wheel 44 is driven from pinion 45 mounted on the shaft 46 with the

spur wheel 47 which is driven from the spur gear 48. Spur gear 48 is mounted on the sleeve 8. In order to have a zero point for timing the pointer 43, pointer 49 is provided 55 which may be rotated to any desired position on the dial by means of the knurled knob 50. Pointer 49 is supported on supporting member 51.

As shown in Fig. 2, the sending of impulses is done by means of a diagrammatically shown calling dial 52, the source of current 53 being also shown diagrammatically. The calling dial 52 and the battery 53 are connected to the binding posts 42 by 65 means of conductors 54.

What is claimed is:

1. In a device for timing a series of electrical impulses, a continuously operating mechanism a time indicating means, a clutch 70 connecting said mechanism, with said means, a catch member normally preventing the operation of said means, a stepping magnet operative by the electrical impulses, a cam rotated by said stepping magnet, and 75 a lever operated by said cam to control said catch member.

2. In a device for timing a series of electrical impulses, a time indicating means normally held against movement, means 80 operated by the first impulse of a series to release the time-indicating means, means acting automatically at the end of said series to stop the time-indicating means, a continuously operating driving mechanism for 85 the time-indicating means and a continuously moving pointer operated thereby, by means of which the time-indicating means is adapted to be timed.

3. In a device for timing a series of electrical impulses, a continuously operating mechanism, a time-indicating mechanism actuated thereby and normally held against movement, means operated by the first impulse of a series to release said timing 95 mechanism, and means operated automatically at the last impulse of said series to stop said timing mechanism.

In witness whereof, I hereunto subscribe my name this 30th day of August, A. D., 100 1920.

CHARLES DONAT RICHARD.
